(57) **CLAIM**

The ornamental design for a USB (universal serial bus), as shown and described.

DESCRIPTION

FIG. 1 is a top perspective view of a USB (universal serial bus) showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof;

FIG. 9 is a perspective view showing a first environment of use; and,

FIG. 10 is a perspective view showing a second environment of use.

The dash-dash broken lines in the drawings depict the portions of the USB (universal serial bus) that form no part of the claimed design. The additional dash-dash broken lines in FIGS. 9 and 10 depict environment and form no part of the claim design.
